R. L. MORROW

SAFETY DEVICE

Filed Dec. 5, 1924

INVENTOR
Robert Lee Morrow
BY
Wallace White
ATTORNEY

UNITED STATES PATENT OFFICE.

ROBERT L. MORROW, OF MERIDEN, CONNECTICUT.

SAFETY DEVICE.

Application filed December 5, 1924. Serial No. 754,050.

To all whom it may concern:

Be it known that I, ROBERT L. MORROW, a citizen of the United States of America, residing at Meriden, Connecticut, have invented new and useful Improvements in Safety Devices, of which the following is a specification.

My invention has for its object to provide means to prevent accidents, such as the loss of fingers and hands, and the mutilation thereof, on machines and tools, such as are in general use in mills and factories throughout the country; a particular instance being power-driven circular wood-cutting saws, which are responsible for a great many of these accidents. The attempts that have been made to overcome this problem have consisted usually in providing mechanical guards covering the saw, which fail of their purpose, first, because they interfere with the view of the work, and are therefore often removed by the operator; and second, because they do not guard the saw at the point where the work is being cut, which is the danger point; and often the worker pushes the wood up against the saw with his thumb behind it, and loses the thumb before he realizes that he is hurt.

The principal object of my invention is to provide means for preventing the worker from coming into contact with the saw or other tool, without interfering with his view of the tool, or access thereto, or the feeding of the work; and I have found an effective way to accomplish such object in providing means for giving a certain and unmistakable warning of the fact that his hand or other part of the body is approaching close to the danger point. A further object of my invention is to give such warning before he has come into contact with the dangerous moving parts of the machine and before he has been hurt; and in such a way as to cause him instantly and involuntarily to draw back from the source of danger. A further object of my invention is to give an electric warning by way of shock or burning sensation to the worker if his hand or any other part of his body approaches too close to the danger point, the shock or burn being, of course, of such a nature as not to be harmful in themselves.

With these and other objects in view, my invention consists in the method, construction, and combination and arrangement of

parts described and claimed herein, and illustrated in the accompanying drawings, in which similar reference characters designate corresponding parts in the several views. I have shown by way of illustration my invention as applied to a circular wood-cutting saw.

Figure 1 is a perspective view of a work table cut away to show a saw and mechanism associated therewith;

Fig. 2 is a sectional view taken approximately through the center of the shaft carrying the saw shown in Fig. 1, on a larger scale, showing the parts of the invention applied thereto; and

Fig. 3 is a diagram of the electrical connections illustrative of the parts contained in the box 8 of Figs. 1 and 2.

Referring to these drawings, the circular saw 1 is mounted between flanges 2 upon a shaft 3, which revolves in bearings 4, mounted upon the frame 5, beneath the table 6. The shaft 3 is revolved by a belt 7 or other suitable means in the usual manner. Any or all of these parts, except of course the saw, may be and preferably are of insulating material. It is essential that the saw be insulated from the ground.

At a convenient point adjacent to the saw 1 is mounted, preferably in a box 8, suitable means for producing a high frequency, high electric potential, in the neighborhood of 40,000 volts, more or less.

Any suitable apparatus may be used for producing the high frequency, high electric potential required, there being several well-known methods all producing frequencies higher than used for ordinary low frequency commercial lighting or power. Details of this apparatus are not material to my invention, but in Fig. 3 I have shown diagrammatically the wiring of a suitable type of apparatus. An ordinary low voltage current, alternating or direct, is applied to the primary circuit flowing through the wire 21, the coil 11, the wire 23, and the coil 13, and the wire 22, magnetizing the iron core of the coil 11 and drawing over the armature 12, thus breaking the primary circuit through the large primary coil 13 of relatively few turns and inducing a current of high potential in the coil 16. The condenser 15 aids in producing a quicker break and reduces sparking at the interrupter points, also increasing the potential due to

the accumulated charge. As soon as the circuit is broken, the core of the coil 11 becomes demagnetized, and the armature 12 closes the primary circuit again. This opening and closing of the circuit takes place repeatedly in rapid succession, producing an oscillating current in the primary coil 13, which is transformed in the secondary winding 16 into a very high voltage oscillating current, the voltage depending on the number of turns of wire in the secondary 16 in relation to the number of turns in the primary 13 and the voltage applied to the primary. The secondary 16 would normally have thousands of turns. The terminal 17 of the secondary is connected, as directly as possible, to a conductor disposed adjacent the danger point, or preferably to the source of danger itself,— as illustrated, the saw. Terminal 19 is suitably grounded.

The potential is sufficient so that a spark will jump from the saw or other charged part of the mechanism a distance of about 2 inches, in practice, more or less, as the potential is varied, so that when the hand or other part of the body of the worker approaches the saw to within a couple of inches thereof, the saw immediately gives out a spark and causes a shock and burn causing him instantly and involuntarily to withdraw his hand away from the saw.

The high frequency, high potential used is substantially that used by doctors in the treatment of various maladies, and when applied to the human body, the small amount of current which flows at the high frequency high potential has a beneficial effect rather than otherwise upon the body.

The potential being so high, the conductor leading it to the danger point must be carefully insulated, and it is desirable that it be short. As shown, I prefer to make the shaft 3 and flanges 2 holding the saw 1 thereon of non-conducting material. The shaft 3 may be provided with a shoulder against which one flange 2 abuts and the other may be held on and the saw clamped by means of a flanged threaded cap or sleeve 9, screw-threaded upon the end of the shaft, and between the shaft and the flanges 2 forming a seat for the latter. This cap or sleeve 9 is of conducting material, and is in contact with the saw 1, and may have formed thereon an exposed contact point 32 which projects outwardly and makes contact with a suitable fixed contact member 18 connected with the terminal 17 of the coil.

In order to provide a definite and effective ground, the table is preferably covered by a metal plate 25, which extends to within about $2\frac{1}{2}$ inches of the saw, and is connected with a metal plate 26 on the floor surrounding the table on which the operator stands. The plates 25, 26 are connected

electrically, as by wire to the negative side 19 of the high frequency coil.

While I have described my invention as applied to a wood-cutting saw, it is to be fully understood that it is applicable to any form of dangerous tool where a high frequency high potential can be maintained at or near the danger point and insulated from the ground.

The operation of the device is as follows: 75

When the saw or other tool is started up for use, the current is also caused to flow through the primary circuit 21, 22, causing the interrupter 12 to operate in the manner described, so that a high frequency, high electric potential is induced in the coil 16, and led by the conductor 17 through the contact 18 to the contact point 32, and through the sleeve 9 to the saw itself, thus charging the latter with the high frequency, high potential. This high frequency high potential is maintained upon the saw, without interference in any way with the working of the saw, and without hampering the worker in any way. The operator stands upon plate 26 and in feeding the work to the saw his hand generally touches plate 25, both of these being connected to the negative of the high frequency coil; thus the operator is "grounded." If, and when, his hand or other part of his body approaches within a predetermined distance, say two inches, more or less, of the saw, due to the high frequency, high potential of the saw, a spark jumps from the saw to the hand or nearest part of the body of the worker, giving him a shock or burning sensation which causes his muscles to involuntarily contract, and causes him to withdraw from danger on receipt of this warning and before he is hurt.

Having now described my invention, I claim and desire to secure by Letters Patent:

1. The method of guarding a dangerous tool which consists in insulating said tool from the ground, and applying a high frequency, high electrical potential thereto. 110

2. The combination comprising a tool, means for applying a high frequency, high electrical potential to said tool, and means for insulating said tool from the ground. 115

3. The combination comprising a cutting or other dangerous tool, and means for maintaining a high frequency, high electrical potential adjacent the danger point. 120

4. The combination comprising a cutting or other dangerous tool, a source of electric current, means for increasing the frequency and stepping up said current to a high frequency, high electrical potential, a terminal insulated from the ground disposed adjacent the danger point, and a connection between said means and said terminal. 125

5. The combination comprising a circular saw, a table and frame on which said saw 130

is insulated and revolvably mounted, and means for applying a high frequency, high electrical potential to said saw.

6. The combination comprising a circular saw, a table and frame at least partly of insulating material on which said saw is revolvably mounted, and means for providing a high frequency, high electrical potential adjacent the cutting edge of said saw.

10 7. The combination comprising a circular saw, a table and frame upon which said saw is mounted and insulated from the ground, means for applying a high frequency, high electrical potential to said saw, a conducting plate for the operator to be in contact with, and a ground connection from the said means for applying the high frequency, high electrical potential leading to said plate.

20 8. The combination comprising a circular

saw, a table and frame upon which said saw is revolvably mounted and insulated from the ground, a conducting plate upon the surface of said table approaching to within a few inches of said saw, and means grounded upon said plate for applying a high frequency, high electrical potential to said saw. 25

9. The combination comprising a circular saw, a table and frame upon which said saw is revolvably mounted and insulated from the ground, a conducting plate upon the surface of said table approaching to within a few inches of said saw, a further plate surrounding said table for the operator to stand upon, and means grounded upon said 30 35 plates for applying a high frequency, high electrical potential to said saw.

In testimony whereof I have signed my name to this specification.

ROBERT L. MORROW.
